UNITED STATES PATENT OFFICE.

HARRY T. STAATS, OF TOWNSEND, DELAWARE.

VENTILATING SHADE-ROLLER.

1,157,261.

Specification of Letters Patent.

Patented Oct. 19, 1915.

Application filed March 4, 1914. Serial No. 822,319.

To all whom it may concern:

Be it known that I, HARRY T. STAATS, a citizen of the United States, and residing at Townsend, in the county of New Castle and State of Delaware, have invented certain new and useful Improvements in Ventilating Shade-Rollers, of which the following is a specification.

This invention relates to new and useful improvements in shade rollers and more particularly to that class adapted to be used for ventilating purposes.

An object of this invention is the provision of a shade roller for ventilating purposes that will eliminate the use of brackets, rods, and all fixtures now used in combination with the ordinary shade roller to produce a means whereby ventilation may be produced by lowering the upper sash of a window and also lowering the shade roller to the same height, thereby permitting ventilation above both.

A still further object of this invention is the provision of a shade roller for ventilating purposes, whereby the upper sash of a window may be lowered and the entire shade and roller lowered likewise, and at the same time permitting the shade to be operated upon the roller therefrom.

With the above and other objects in view, this invention resides in the novel features of construction, formation, combinations, and arrangements of parts to be hereinafter more fully described, claimed and illustrated in the accompanying drawings, in which:—

Figure 1, is a front elevation of a window with my ventilating shade roller applied thereto, Fig. 2, is a front elevation of my roller with shade removed, Fig. 3, is a perspective of the guide arm, and operating lever, Fig. 4, is a longitudinal sectional view of my roller, Fig. 5, is a top plan view of the main shaft, with tubular casing thereon, Fig. 6, is a top plan fragmentary view of a portion of my roller with parts broken away, Fig. 7, is a side elevation of the capping plug, with plate thereon and Fig. 8, is a front elevation of the same.

Referring to the accompanying drawings by similar characters of reference, the numeral 10 denotes in general my ventilating shade roller, which comprises the customary roller 11 to which the shade 12' is applied. This roller 11 consists of the customary hollow casing end 12 and solid end 13, the latter end having a longitudinal recess 14, formed therethrough, of greater diameter than the diameter of the main shaft 15, this being produced to permit the said shaft 15 to freely rotate therein, without contacting 60 with the inner face of the recess, while the outer end of this solid portion 13 has a crimped cap A mounted thereon, and which holds substantially in position a metal plate C, having a suitable aperture formed there- 65 in for the reception of the main shaft 15, thereby producing a bearing for the same and by means of which the shaft is pre- vented from contacting with the previously mentioned inner face of the recess 14. This 70 shaft 15 runs longitudinally through the entire length of the roller 11 and in the center thereof, extending a limited distance therefrom at opposite ends thereof, the ob- ject of which will be hereinafter more fully 75 described.

Mounted upon the main shaft 15 in the hollow casing end 12 and substantially held in position by a set screw 16 is a tubular casing 17 of suitable length to conform with 80 that of the coil spring 18, mounted thereon, one end of which is secured thereto as at 19, while the opposite end of the same is se- cured to the tapering end 20 of a capping plug 21 and secured thereto as at 22. This 85 capping plug 21 being tapered at one end to conform with that of the thickness of the tubular casing 17 mounted upon the main shaft 15, thus snugly contacting with the same as at 23, while the opposite end of this 90 plug has a metal plate B secured thereto which is larger in diameter than the body portion of the capping plug 21, thus pro- ducing a flange 24 thereon of a suitable width so as to neatly cap the outer end of 95 the hollow casing end 12 as at 25, while the body portion of this plug 21 is of a suitable length and thickness as designated by the numeral 26' so as to extend for a limited dis- tance into the hollow casing 12 and fit 100 snugly therein, the same being securely held therein by means of screws 26; thus it will be readily seen that this plug is stationary in the casing 12 and co-operates with the roller 11, both being rotatable upon the main 105 shaft 15, but the movement of both being limited as desired by dogs 27 and 28, se- cured to the outer face of the metal plate B of the capping plug 21. This capping plug 21 also has a longitudinal recess formed 110 therethrough for the reception of the main shaft 15 and of greater diameter than the

same, this being produced for the same purpose as that of the recess formed in the solid end 13 previously mentioned, while the metal plate B is secured to the capping plug 21 by any suitable means and has formed therein a suitable aperture to produce another bearing for the main shaft 15, which also prevents the same from contacting with the inner face of the recess formed in the said plug, thus producing a bearing for the said shaft at each end of the roller 11.

Rotatable upon the main shaft 15 and mounted thereon at one of the extended ends thereof is a sleeve 29, having a guide arm 30 extending upwardly therefrom and terminating into an outwardly extending arm 31, having an enlarged portion 32 formed thereon with a longitudinal slot 33 formed therein, through which passes a cord 34' to be later described. This sleeve 29 has notches 35 and 36 formed therein, the notch 35, being notched in an opposite direction to that of the notch 36, this notch coöperating with the dogs 27 and 28, mounted upon the face of the metal plate B of capping plug 21, while the opposite notch 36 coöperates with the dogs 37 and 38, mounted upon the inner face of a spool 39; thus it will be readily understood that the first mentioned dogs 27 and 28 operate in the opposite direction to that of the last mentioned dogs 37 and 38. This spool 39 is mounted upon the extended end of the main shaft 15 in advance of the sleeve 29, and substantially secured thereto by means of a set screw 40, while mounted at the opposite end of the main shaft 15 and in advance of the solid end 13 and cap A of the roller 11 is another spool 41 also substantially mounted upon the extended end of the main shaft 15 and secured thereto by means of another set screw 42. The spool 39 has a flange 43 extending outwardly from the inner face thereof thereby producing a cup like inner face, this flange 43 having a tendency to limit the backward movement of the dogs 37 and 38 operating therein, while the same movement with the dogs 27 and 28 by means of a band 44 which encircles the hollow casing end 12 and extends slightly in advance of the capping plug 21 as at 45. This band is of a double thickness at this point, being crimped to further assist in securely holding the capping plug 21 in position.

The spools 39 and 41 are for the reception of cords 34 and 34', both of which have one end secured thereto by suitable means, while the opposite ends extend upwardly from the spools and are secured to the window frame by screw eyes 46 or the like, thus it will be seen that the said screw eyes are the only fixtures needed with which to apply my shade roller to a window frame. The cord 34' extending upwardly from the spool 39 passes through the slot 33 formed in the outwardly extended arm 31 of the guide arm 30,

thereby preventing the sleeve 29 from rotating upon the main shaft 15 when my roller is in operation and furthermore producing a guide for the cord 34' passing therethrough. Directly below the guide arm 30 and formed from the same sleeve 29 is a downwardly extending operating arm 30' having an aperture 47 formed therein for the reception of an operating cord 48 by which my ventilating roller in general is operated.

The spools 39 and 41 are to be supplied and have wound thereon a suitable amount of cord or the like, of suitable strength to permit the operation of my roller for ventilating a window of any length, and the operation of my roller will now and hereafter be more fully described as follows:— After securing screw eyes or the like in position on the desired window, the ends of the cords 34 and 34' are secured thereto and my roller is then in a position to be readily operated. To lower the roller independently, the operator upon pulling the cord 48, releases one of the dogs 37 and 38 engaging the notch 36 formed in the sleeve 29, these dogs being mounted on the inner cup like face of the spool 39, and upon being released from their respective positions, allow the operator to readily lower the roller independently as far as desired and upon releasing the operating cord, the tension of the coil spring, upon the main shaft turns the same in the opposite direction for a limited distance until one of the said dogs falls into the respective position with the notch again, thus holding the roller at the point desired by the operator.

When it is desired to have the roller returned to its respective position at the top of the window, upon releasing the dog again, the roller winds back to its respective position, traveling upon the cords 34 and 34', this movement being caused by the tension of the coil spring, coöperating with the main shaft 15, this shaft having the spools upon which the cords 34 and 34' wind thereon, and the said spools being substantially secured thereto by set screws. Thus it will be clearly understood that this roller will operate and travel up and down the cords 34 and 34' in the same manner that the ordinary shade operates upon the customary shade roller.

The operation in raising and lowering the roller independently does not interfere in any way with the shade operating upon the roller, as the same may be operated in the customary manner therefrom by means of the dogs 27 and 28, coöperating with the notch 35 in the sleeve 29 together with the coil spring also having tension on the roller 11 proper, owing to the fact that one end of the said spring is secured to the capping plug, which is substantially mounted within the said roller and secured thereto, thus pro-

ducing the same function as that produced by the ordinary shade roller now on the market.

It is to be remembered that the spools 39 and 41 both being substantially mounted on the main shaft, will rotate with the same, the main shaft rotating within the roller 11, while the roller does not rotate upon the shaft until the shade is to be operated, then the roller rotates upon the shaft and operates independently therefrom.

It is now thought that the above description together with the accompanying drawings should readily give those familiar with this art, a clear explanation as to the operation of this roller, and it should be understood in this connection that various minor changes in the details of construction can be resorted to within the scope of the appended claims, without departing from or sacrificing any of the advantages of this invention.

From the foregoing disclosure taken in connection with the accompanying drawings, it will be manifest that a ventilating shade roller is provided, which will fulfil all of the necessary requirements of such a roller.

Having thus fully described this invention, what I claim as new and wish to protect by Letters Patent is:—

1. A shade roller mounted upon a main shaft, a tubular casing secured to said main shaft, a coil spring mounted thereon, a spool mounted upon each end of the main shaft, each of said spools having a cord wound thereon, said cord having one end secured to said spools and the other end extending therefrom and secured to a window facing, a sleeve mounted upon the main shaft between one end of said roller and one of said spools and held against displacement by the

same, a guide arm extending upwardly therefrom and terminating in another arm having an aperture formed therein as a guide means for the cord extending from one of said spools and an operating arm extending downwardly from said sleeve as and for the purpose set forth. 45

2. A shade roller comprising a casing, a main shaft mounted therein and extending therefrom a limited distance at both ends thereof, a tubular casing mounted within the first mentioned casing and secured to said main shaft, a coil spring mounted upon said last mentioned tubular casing and having one end secured thereto, a capping plug secured at one end of said roller and extending therein a limited distance and having secured thereto the opposite end of said coil spring, a spool mounted upon the extended ends of said main shaft, a sleeve mounted upon the said main shaft intermediate one end of the roller and one of said spools, said sleeve being rotatable therebetween and having a plurality of notches formed therein, a plurality of dogs mounted upon one end of said roller for engagement with one of said notches, one of said spools having a cuplike inner face formed thereon and a plurality of dogs mounted therein for engagement with another of said notches, a guide arm extending upwardly from said sleeve and terminating in an outwardly extending arm having an aperture formed therein and an operating arm extending downwardly from said sleeve as and for the purpose set forth. 65 70 75

In testimony whereof I affix my signature in presence of two witnesses.

HARRY T. STAATS.
